UNITED STATES PATENT OFFICE.

DAVID B. CONCLIN, OF NEWPORT, KENTUCKY.

WINDLASS.

1,379,084.

Specification of Letters Patent. Patented May 24, 1921.

Application filed September 11, 1918. Serial No. 253,597.

To all whom it may concern:

Be it known that I, DAVID B. CONCLIN, a citizen of the United States, residing at Newport, in the county of Campbell and State of Kentucky, have invented new and useful Improvements in Windlasses, of which the following is a specification.

This invention relates to an improved windlass especially designed for use in connection with the manufacture or repair of barrels, such as sugar or flour barrels and the like, although it is of course capable of use in various other connections, the object being to provide a windlass by means 15 of which shrunken barrels or tanks may be tightened.

Another object of the invention is to provide a windlass which may be placed at various positions upon the outside of the 20 barrel and in which the ratchet operating mechanism is positioned out of the way of the tightening rope or cable, thereby preventing undue wear upon the latter or damage to the ratchet mechanism.

25 To this end the invention includes a pair of plates held in spaced relation by spacing rods or bolts and having mounted for rotation between them a winding drum, the ratchet mechanism being so mounted upon 30 one trunnion of the drum upon the outer side of the plates as to be out of the path of the rope or cable. The plates are provided with curved flanges along one of their edges for contact with the periphery of the 35 barrel.

The invention also includes the following novel construction, combination and arrangement of parts to be hereinafter more fully described and illustrated in the drawings, in which:

Figure 1 is a view in side elevation of a fragmentary portion of the barrel illustrating the application of the invention;

Fig. 2 is a top plan view of the windlass 45 detached from the barrel;

Fig. 3 is an enlarged sectional view on the line 3-3 of Fig. 1; and

Fig. 4 is a detail perspective view of one of the bearing plates.

50 Referring to the drawings in detail, wherein like characters of reference denote corresponding parts, the improved windlass includes upper and lower bearing plates 10 and 11 respectively, the said plates being 55 of different size so as to conform to the

outer rounded surface of the barrel. These plates are secured together in spaced relation through the medium of bolts or rods 12, spacing ends 13 being provided upon the rods for the purpose of holding the plates 60 in position. One edge of each of the plates is curved, as shown at 14 and this curved edge is provided with an angularly disposed flange 15, the latter being adapted to fit the transverse curvature of the barrel. 65

Mounted between the plates 10 and 11, is a drum 16, the outer surface of which is concaved, each end of this drum is provided with a trunnion 17, which passes through bearing openings 18 in each of the 70 plates 10 and 11. The trunnion 17 which passes through the plate 10 has secured thereon a ratchet wheel 19, the said wheel being mounted upon the trunnion 17 upon the side of the plate opposite the drum 16. 75 Also mounted upon the plate 10 is a dog 20, a bracket 21 being spaced from the plate and a dog 20 mounted within this space upon a pivot 22. The dog 20 is adapted to engage the teeth of the ratchet wheel 19, 80 a spring 23 serving to hold the dog in such engagement. Mounted for free rotation upon the trunnion 17 above the ratchet wheel 19 is a lever 24, this lever being mounted between the wheel 19 and the ratchet wheel 25 fast 85 upon the trunnion 17. The ratchet wheel 25 is engaged by a dog 26 carried by the lever 24, this dog being also forced into engagement with the ratchet wheel by a spring 27. The outer end of the lever 24 carries an 90 operating handle 28.

The drum 16 is provided with a transverse opening 29 for the passage of a rope or cable, the latter being adapted to encircle the barrel so that rotation of the drum 95 through the medium of the ratchet mechanism will cause the tightening of the rope or cable so as to draw the sides of the barrel tighter together. The hoops may then be tightened by tapping them with a hammer or other tool to move them upon the larger circumference of the barrel. 100

The invention is susceptible of various changes in its form, proportions and minor details of construction and the right is reserved to make such changes as properly fall within the scope of the appended claim.

Having described the invention, what is claimed is:-

In combination with a flexible tension 110

element to be passed around a cooperage article for drawing the staves together, a frame having laterally extended faces to bear on segmental parts of said article at opposite sides of the plane of the passed-around tension element, a drum rotatably mounted in said frame, said tension element being connected to said drum for winding thereon to contract said element

around said article, an operating handle 10 having a sweep in a plane substantially parallel with said plane of said passed-around tension element, and a ratchet mechanism operatively connecting said operating handle to said drum.

In testimony whereof I affix my signature.

DAVID B. CONCLIN.
